SAFETY LENS ATTACHMENT

Joseph B. Dym, 115 W. 7th Ave., Homestead, Pa.

Filed Feb. 10, 1965, Ser. No. 83,769

Term of patent 14 years

(Cl. D57—1)

Fig. 1.

Fig. 2.

Fig. 3.

FIG. 1 is a top perspective view of a safety lens attachment for eyeglasses,

FIG. 2 is a rear perspective view thereof; and,

FIG. 3 is a side perspective view thereof.

The broken line showing of the eyeglasses in FIG. 1, portions of the temple of which are shown broken away for convenience of illustration, is for illustrative purposes only.

I claim:

The ornamental design for a safety lens attachment, substantially as shown and described.
